ROTARY SURFACE-FINISHING TOOL

Ruben O. Peterson, University Heights, Ohio, assignor to The Osborn Manufacturing Company, Cleveland, Ohio, a corporation of Ohio

Application April 30, 1949, Serial No. 90,585

3 Claims. (Cl. 51—186)

1

This invention relates as indicated to a novel rotary surface-finishing tool and, more particularly, to a tool especially adapted to clean, polish, etc. the interior surfaces of blind holes and the like.

Various types of rotary brushes have been employed in the past for the purpose of cleaning and surface finishing tubular articles such as boiler tubes and the like but no such tool has been available which would simultaneously similarly clean or finish the end of a blind opening. The ordinary type of twisted wire stem brush is, of course, unable to perform any such function since the brush material therein extends only laterally and, in fact, care must ordinarily be taken to see that the end of the brush does not actually contact the blind end of the opening since otherwise the stem portion thereof may actually mar the work, and the brush material may become distorted. For this reason, it is usually impossible as a practical matter even to brush the lateral surfaces of the hole closely adjacent the inner end thereof.

It is therefore a primary object of my invention to provide a novel rotary tool adapted to clean, polish and surface condition not only the lateral surfaces of an opening in a work-piece but also simultaneously a blind end of such opening.

It is a further object of this invention to provide such tool which will be very inexpensive of manufacture and which is readily adapted for use with such standard rotary driving means as drill presses, hand drills, and the like.

Still another object of my invention is to provide a tool of the type indicated in which the surface-finishing material is firmly held and which will therefore have a relatively long life.

Other objects of the invention will appear as the description proceeds.

To the accomplishment of the foregoing and related ends, said invention then comprises the features hereinafter fully described and particularly pointed out in the claims, the following description and the annexed drawing setting forth in detail certain illustrative embodiments of the invention, these being indicative, however, of but a few of the various ways in which the principle of the invention may be employed.

In said annexed drawing:

Fig. 1 is a perspective view of one typical embodiment of my new rotary tool;

Fig. 2 is a form of such tool modified for ease of manufacture;

Fig. 3 is a similar form of tool contoured to operate within a stepped opening;

Fig. 4 is a brushing element adapted to be employed in my new tool and comprising a plurality of layers of screen material secured together;

Fig. 5 is an edgewise view of such element;

Fig. 6 shows a tool including such element, the latter being sectioned centrally thereof;

Fig. 7 shows a holder adapted to be employed in conjunction with the tool of my invention;

Fig. 8 shows such holder with such tool secured therein;

Fig. 9 is an end view of the tool and holder combination of Fig. 8; and

Fig. 10 shows a helically formed tool of the twisted stem type made in accordance with my invention.

Referring now more particularly to said drawing and especially Figs. 1-3 thereof, I may employ a rectangular section of sheet material such as 20 felt 1, having appreciable thickness, as the operative or "brushing" element. As shown in Fig. 1, a wire 2 may be inserted through a hole 3 spaced from the edge of such felt element and then doubled and twisted upon itself to form a twisted stem 4. The layer of felt is thus firmly secured between the straight parallel retaining portions 5 of the wire stem member.

Ease of manufacture is greatly increased if a narrow slot 6 is provided extending from hole 3 to the lower edge 7 of the felt element extending in the direction opposite to stem 4. When assembling the tool, the wire member may then be passed laterally through such slot either prior to doubling of the wire or after such wire has preliminarily been formed into an open loop rather than requiring that the end of the wire be passed through the hole 3. The end portions of such open wire loop are then, of course, twisted together to form the stem 4 and to tightly secure the felt element between the parallel retaining portions 5.

As shown in Fig. 3, the sides and ends of the felt element may be trimmed or shaped to any desired contour to adapt the same to the shape of the particular opening to be operated upon. In this instance a stepped construction is shown with the portion 8 of the felt element adjacent the end of the latter having a lesser lateral dimension than the upper portion 9. It is, of course, apparent that such element may be trimmed to a tapered, semi-circular, or any other desired form as long as such element is symmetrical relative to its axis as defined by the wire stem retaining member.

Referring now to Figs. 4-6 inclusive, there is

there illustrated another modified form of my new rotary tool which in this instance comprises a plurality of layers of woven wire cloth 10 bound together by means of a suitable plastic material such as rubber, neoprene (polychloroprene), melamine, or nylon (polyamide resins), for example. The wire stem member is inserted through the hole 11 as shown in Fig. 6 and twisted to form the stem 4 similarly to the Fig. 1 construction. Any of the powdered abrasives such as Carborundum or Alundum, for example, may be incorporated with the bonding material which is ordinarily an elastomer. For ease of assembly of the operating element the bonding material such as neoprene may be provided in sheet form and alternate layers of such sheet and the wire cloth may be stacked one upon the other, compressed under pressure, and the neoprene then cured. As in the case of the Fig. 3 construction, the finished element may likewise be cut to desired contour. It will of course be apparent that when the wire stem member is parallel to one set of strands composing the wire mesh there will be provided "brushing" strands operative to act upon both the sides and end of a blind passage. If desired, the several layers of wire cloth or screening may be superimposed and bonded together with the component strands of one layer lying at an angle to strands of other layers, and this may be desirable in certain instances as where the finished element is to have a tapered contour, for example.

Tools of the type above described may desirably be mounted in holders (Fig. 7-9) comprising a tubular portion 12 and a shank 13 adapted to be inserted in a drill press collet, for example. Bore 14 of tubular portion 12 is dimensioned to receive the twisted stem 4 of my new tool with the brushing element 15 held and supported in transverse slot 16 in the end of such tubular portion 12. The "brushing" element 15 corresponds to the element 1 of Fig. 1 or any of the various modifications thereof. A set screw 17 may be employed to secure stem 4 in place. It will thus be seen that means is provided for supporting the "brushing" element in a convenient manner permitting ready replacement of the latter when necessary, and without any danger of either the wire retaining member 5 or of tubular holder 12 contacting and damaging the work-piece.

In Fig. 10 there is illustrated another embodiment of my invention wherein a strip of felt 18, similar to element 1 of Fig. 1 but much more elongated, is clamped between retaining wire portions 19 doubled through hole 20, which latter wire portions are twisted after formation of twisted stem portion 4 to impart a helical configuration to such strip of felt as shown. The end of the latter is, of course, adapted to act upon the end of a blind hole or passageway and further serves to prevent contact of the doubled retaining wire with the work.

While the felt or other operating element may ordinarily be sufficiently firmly secured between the wire portions 5 simply by twisting such portions together as explained, it is often desirable to forcibly press such wire portions together, as between dies, to compact and secure such element therebetween. Pressures on the order of 10,000 to 20,000 lbs. per square inch or more may sometimes be imposed although considerably lower pressures are sufficient where the operating element is of relatively compressible material. Where high pressures are employed, the wire will desirably have a flat face, as with half-round

wire, which will be directed toward the element to obviate any danger of cutting the latter. A more rigid structure is likewise obtained and flexure is not concentrated along a single line in use.

When a tool of the Fig. 10 type is to be produced having a relatively long strip of material to be secured between retaining wire portions, it is particularly desirable that such portions be flat faced as above described and that the material be compacted therebetween by application of pressure. The stem portion 4 will then preferably be twisted prior to twisting of such retaining portions.

The operating or "brushing" element may comprise a wide variety of materials, as above indicated. Such materials should, however, be self-supporting (i. e. not limp) and will be selected for the particular use contemplated. Thus, layers of abrasive paper or abrasive cloth, or layers of each, may be bonded together, preferably by means of an elastomer, to form such element of my new article. The paper or cloth will desirably have abrasive adhered to both sides thereof before being assembled to form the element. Such element, while self-supporting, should not be entirely rigid but should be capable of flexing in use. The woven-wire cloth 10 will therefore preferably be of wire of the type used in power brushes having a certain resilience and snap action. Layers of cotton fabric buff material and similar fabrics may be stapled or riveted together rather than bonded if a softer buff-type element is desired and, in fact, in some cases the clamping action of the wire retaining member may be relied upon to secure a plurality of such layers of sheet material without any means being provided actually attaching the layers together.

The surface-finishing element will thus be seen to comprise a generally flat sheet of substantial thickness (so as to present an effective work-contacting surface) of flexible material, which for many purposes will also be resilient in character. Such element should of course be of a contour symmetrical relative to the wire stem member which defines the axis of rotation.

The wire stem member may be considered as passing through the body of the surface-finishing element whether it is forced through, inserted through a hole, or doubled through a notch therein. In any event, the point of doubling of such member is located inwardly from the end of the element and therefore cannot contact the work. Such doubled portions may be secured together beyond the body of the surface-finishing element by other means than by twisting together, as by soldering, clipping or wrapping, or insertion in a suitable holder. Twisting is ordinarily a suitable method, however, being quick and inexpensive, and, even when pressures in excess of the tensile strength of the wire are required to be imposed to compact the body of the surface-finishing element between the doubled portions of the wire, when such element has been thus compacted the wire will be found sufficiently strong to retain the material in compacted state. Instead of steel or other metal wire, it will be apparent that equivalent elongated stem members of suitable synthetic plastic materials may be employed.

While, in the Fig. 10 embodiment, an elongated rectangular sheet or strip 18 is shown with the wire 19 passed therethrough at a point on the longitudinal axis adjacent one end thereof, it will be understood that such end may instead be slotted or notched to receive the doubled wire.

Also, the strip or sheet of surface-finishing material may, for example, be of greater width adjacent the twisted stem 4 and taper toward the end, depending on the particular operation for which the tool is designed.

The term "surface-finishing" as employed herein is intended to include cleaning, polishing and like operations.

Other modes of applying the principle of the invention may be employed, change being made as regards the details described, provided the features stated in any of the following claims or the equivalent of such be employed.

I therefore particularly point out and distinctly claim as my invention:

1. A rotary tool comprising in combination a working element and a holder therefor; said element comprising a sheet of substantial thickness of self-supporting flexible material and a wire stem member passing through said sheet and doubled upon itself to clamp such material between straight parallel portions of said member, such portions extending beyond said sheet to form a stem; and said holder comprising a tubular member adapted to receive such stem therein, with the end of said tubular member being slotted to receive said sheet and thereby support the side and end portions of the same, the depth of such slot being less than the axial extent of said sheet so that a portion of said sheet will protrude axially beyond the end of said tubular member when seated therein; and means securing said stem within said holder.

2. A rotary surface-finishing tool adapted to be rotated at high speeds about its axis simultaneously to act upon both laterally and axially disposed work surfaces, as within a blind hole in a work-piece, comprising a generally flat symmetrical body of flexible self-supporting abrasive material, an elongated stem member formed into

a loop passed through such material at a point spaced inwardly from the edges thereof and doubled upon itself to clamp the flat sides of such material between parallel portions, said member extending beyond said body to form a stem; a holder comprising a tubular member adapted to receive such stem therein, with the end portion of said tubular member being slotted longitudinally thereof to receive said flat symmetrical body of abrasive material and support the same, the axial extent of such slot being less than the axial extent of said body of abrasive material so that a portion of said body will protrude laterally of said tubular member and also axially beyond the end thereof when said body is seated in said slot; and means adapted to secure such stem within said tubular holder.

3. A rotary tool adapted to be rotated about its axis to act simultaneously upon both laterally and axially disposed work surfaces, as within a blind hole in a work-piece, comprising a generally flat symmetrical body of sheet material, an elongated holder member having a longitudinally slotted end with said body of sheet material symmetrically received in such slot and projecting therefrom both laterally and to a lesser longitudinal extent axially of said holder member, and means adapted to secure said sheet material thus positioned in such slot.
